UNITED STATES PATENT OFFICE.

LOUIS E. LEYENS, OF VICKSBURG, MISSISSIPPI.

CASTING MACHINE.

Application filed December 17, 1921. Serial No. 523,151.

To all whom it may concern:

Be it known that I, LOUIS E. LEYENS, a citizen of the United States, residing at Vicksburg, in the county of Warren and 5 State of Mississippi, have invented certain new and useful Improvements in Casting Machines, of which the following is a full, clear, concise, and exact description, reference being had to the accompanying drawings, forming a part of this specification.

My invention relates to improvements in casting machines, and is particularly concerned with the provision of a novel casting machine for casting stereotypes.

15 The objects of my invention are—

First: To produce a casting machine for making stereotypes from the conventional matrix or "mat," which is simple in construction, economical to manufacture, and easy 20 to operate;

Second: To provide a casting machine of the character described for casting stereotypes designed particularly for use upon cylinder printing machines;

25 Third: To provide a casting machine for casting stereotypes for use upon cylinder printing machines in which the cylinders are provided with longitudinally extending slots for anchoring the printing characters;

30 Fourth: To provide a casting machine which can be used with "mats" of different sizes, and

Fifth: To provide a casting machine such as described comprising means for forming 35 depressed margins around the printing face of the stereotype for receiving the usual clamping devices for securing stereotypes to cylinder printing machines.

Other objects will appear as this description progresses, reference being had to the accompanying drawings in which

40 Figure 1 is a plan view of my improved casting machine, portions thereof being broken away for the purpose of better illustration,

45 Figure 2 is a side elevation, the cope member being shown in dotted outline in an elevated position,

Figure 3 is a central longitudinal section, 50 Figures 4 and 5 are transverse sections taken on lines 4—4 and 5—5, respectively, of Figure 1,

Figure 6 is a sectional detail taken on line 6—6 of Figure 1, and

55 Figure 7 is a section corresponding to the

section shown in Figure 4 but showing a modified form of my invention.

Throughout the several views, similar reference characters are used for referring to similar parts, and the sections are taken 60 looking in the direction of the small arrows.

The embodiment of my invention which I have illustrated comprises a drag member 10 having a concave cylindrical casting surface, and a cope member 11 having a convex 65 cylindrical casting surface. At one end, the drag member 10 is provided with two spaced projecting lugs 12 and 13, and the cope member 11 is provided with a third projecting lug 14 which extends between the two lugs 12 and 13 of the drag member (see Figure 70 1). A pintle 15 passing through the lugs 12, 13 and 14 provides a pivot pin upon which the cope member can be turned for a purpose which will be referred to later on. 75 The lug 14 has an extension 16, which is adapted to engage the rear side of the lug 17, which projects downwardly from the drag member 10, to limit the opening movement of the cope member relatively to the 80 drag member.

The drag member is provided with legs 18 for supporting the casting machine in a horizontal position. A stud 19 projecting rearwardly from the lug 17 and studs 20 85 projecting rearwardly from the upper portion of the cope member provide a second set of legs for supporting the casting machine in a vertical position, as will be pointed out later on in this description.

A bar 21 extending between the opposite sides of the cope member re-inforces the rear end of this member, and a flange 22 extending around the rear end of the convex surface of the cope member serves to properly space this end of the cope member from the drag member. Bosses 23 extending inwardly from the convex surface of the opposite end of the cope member perform a similar function.

For clamping the cope member to the drag member, I provide a bracket 24, at each side of the forward end of the drag member. These brackets can be formed integrally with the drag member, or formed separately and secured thereto by means of screws 25. A link 26 has one of its ends pivotally mounted upon each of the brackets 24 by means of a screw 27 passing through a suitable bore in the end of the link and into the bracket 100 105 110

24. A screw 28 is mounted in the free end of each link 26. The upper end of the screw 28 is provided with a cross pin 29 for rotating it. Each side of the cope member adjacent its front end is built up, as shown at 30, to provide a seat for the inner end of the screw 28.

With the construction just described, all that is necessary to do, to secure the cope 10 and drag member together, is to turn the links 26 to the position shown in Figure 1, and turn the screws inwardly until the inner ends engage the seats 30 and securely clamp the cope to the drag member. It 15 will, of course, be understood that the cope member is released from the drag member by a reverse operation.

The mats from which stereotypes are cast are made in many different ways, and usually have depressed portions at their edges indicating margins. To make a stereotype from such a mat with my improved casting machine, the mat is placed on the drag member, as shown in Figure 1, preferably 20 with its longitudinal center substantially coinciding with the longitudinal center of the drag member which, if desired, can be indicated by a mark 31. Other similar marks 31' can be made in the surface of the 25 drag member to enable the operator to properly position the mats. If desired, indicia such as indicated at 32 can also be used to assist the operator.

To hold the mats in the proper positions, 30 I provide a transversely extending margin strip 33 which is curved to conform to the curvatures of the cope and drag members, and is also provided at its rear edge with lugs 34 which are received by the transversely extending grooves 35 formed in the 40 concave surface of the drag member. By this means the mat can be held so that its outer end will be positioned adjacent the outer end of the two casting members, as 45 shown in Figure 1. For holding the sides of the mat, I provide the two longitudinally extending margin strips 36, the sides of which, adjacent the cope, are shouldered as indicated at 37 (see Figures 5 and 6) to 50 provide longitudinally extending recesses for receiving the side edges of the mat.

To make it possible for the operator to adjust the margin strips 36 to different sized mats, I provide suitable clamps, each 55 comprising a body member 38 which is slidably mounted upon an annular rail 39 formed at the front end of the drag member, and each having a longitudinally extending groove 40 formed therein through 60 which the margin strip 36 can slide. A clamping plate 41 has one edge 42 turned inwardly to engage with the margin strip 36 and is provided with an opening through 65 which the stud screw 43 projects. A washer 44 and a nut 45 provide means for clamp-

ing the down turned edge 42 of the clamping plate 41 against the margin strip. A set screw 46 provides means for holding the clamp in any desired position on the rail 39.

In the drawings, margin strips 33 and 36 are shown holding a mat 47 in position adjacent the outer ends of the casting members.

The outer end of the drag member 10 is 75 provided with a gate 48 for directing the type metal into the space between the two casting members.

Where my improved casting machine is used for casting stereotypes for cylinder machines in which the cylinders are provided with longitudinally extending slots for anchoring the printing characters, I prefer to provide the cope member 11 with the longitudinally extending groove 49 which opens through its convex surface. The longitudinally extending rib 49' reinforces the cope member immediately adjacent the groove 49. To prevent metal from flowing down this groove further than the 99 limits of the mat, I provide the margin strip 33 with the upwardly extending lug 50, which fits into the groove 49.

A handle 51 is secured to the cope member by the two brackets 52, one of which is secured to each side of the cope member.

In the use of my improved casting machine, it is placed in a horizontal position, as shown in Figure 2, and the cope member is raised to a point past the vertical position where it is supported by the projection 16 coming into contact with the lug 17. The mat is then secured in position by means of the margin strips, as shown in Figure 1, the two margin strips 36 preferably being arranged so as to bring the longitudinal center of the mat substantially in line with the center line 31 of the drag member. The cope member is then turned over on the drag member and secured by means of the clamps comprising the links 26 and the screws 28. The operator then seizes the handle 51 and lifts the machine to a vertical position in which it will be supported by the legs 19 and 20. The molten type metal is then poured into the gate 48, and passes down between the mat and the cope member.

The casting machine can then be replaced in its horizontal position, the clamps unfastened, and the cope member separated from the drag member. The stereotype can then be removed from the cope member to which it will ordinarily adhere on account of the projecting rib of metal which is cast in the groove 49. It is an easy matter to remove the stereotype from the cope member.

In Figure 7, I have illustrated a modified form of my invention in which the grooves 35 are omitted from the drag member, and

the adjustment of the margin strip 33 is provided by means of a screw 55 which projects outwardly from the margin strip adjacent one end thereof and through a longitudinally extending slot 56 formed in one edge of the drag member. A wing nut 57 provides means for securing the margin strip 33 in any of its adjusted positions.

While I have described the details of construction of the preferred embodiment of my invention, it is to be clearly understood that my invention is not limited to these details but is capable of other adaptations and modifications within the scope of the appended claims, and it is to be particularly understood that my casting machine is not limited to the production of cylindrical stereotypes, but is capable of producing flat stereotypes. Neither is my invention limited to the production of stereotypes upon the backs of which are longitudinally extending ribs.

Having thus described my invention, what I claim is:

25. 1. A casting machine comprising a cope member and a drag member, one of said members having a convex cylindrical surface and the other having a co-acting concave cylindrical surface, the member having said convex cylindrical surface having a longitudinally extending groove opening through its convex surface, the other of said members having a plurality of spaced transversely extending grooves formed in its curved surface, a curved margin strip extending transversely of said last named member and having spaced lugs for engaging the sides of said last named grooves, a pair of longitudinally extending margin strips, a curved rail at one end of the member having the concave cylindrical surface, and a clamp for each of said longitudinally extending margin strips adjustably secured to said rail, said clamps comprising means for adjusting said last named margin strips longitudinally of said members.

2. A casting machine comprising a cope member and a drag member, one of said members having a longitudinally extending groove opening through its convex surface, the other of said members having a plurality of spaced transversely extending grooves formed in its surface, a margin strip extending transversely of said last named member and having spaced lugs for engaging the sides of said last named grooves, a pair of longitudinally extending margin strips, a rail at one end of said last named member, and a clamp for each of said longitudinally extending margin strips adjustably secured to said rail, said clamps comprising means for adjusting said last named margin strips longitudinally of said members.

3. A casting machine comprising a cope

member and a drag member, one of said members having a longitudinally extending groove opening through its convex surface, the other of said members having a plurality of spaced transversely extending grooves formed in its surface, a margin strip extending transversely of said last named member and having spaced lugs for engaging the sides of said last named grooves, a pair of longitudinally extending margin strips, and means for adjusting said last named margin strips transversely and longitudinally of said members.

4. A casting machine comprising co-acting cope and drag members hinged together at one end, one of said members having a longitudinally extending groove opening through its casting surface, a transversely extending margin strip lying between said members, a pair of longitudinally extending margin strips lying between said members, means for adjusting said transversely extending margin strip longitudinally of said members, and means for adjusting said longitudinally extending margin strips longitudinally and transversely of said members.

5. A casting machine comprising co-acting cope and drag members hinged together at one end, a pair of longitudinally extending margin strips lying between said members, means for adjusting said longitudinally extending margin strips transversely of said members, and releasable means mounted on said drag for holding said margin strips in any of their adjusted positions.

6. A casting machine comprising co-acting cope and drag members hinged together at one end, the opposite end of one of said members being provided with a pouring gate, and means extending outwardly beyond the hinged ends of said members for supporting said members in a vertical position to permit molten metal to be poured into said gate.

7. A casting machine comprising co-acting cope and drag members hinged together at one end, spacing studs secured to one of said members for spacing it from the adjacent member, and clamping members for securing said cope and drag members together, said clamping members each comprising a bracket member pivoted to one of said members and adapted to be swung over the other member, and a screw carried by the free end of said bracket member, the axes of said bracket and said screw being parallel.

8. A casting machine comprising co-acting cope and drag members hinged together at one end, spacing studs secured to one of said members for spacing it from the adjacent member, and clamping members for securing said cope and drag members together.

9. A casting machine comprising a cope

member and a drag member, one of said members having a plurality of spaced transversely extending grooves formed in its casting surface, a margin strip extending transversely of said last named member and having spaced lugs for engaging the sides of said grooves, a pair of longitudinally extending margin strips, a transversely extending rail at one end of the said last named member, and a clamp for each of said longitudinally extending margin strips adjustably secured to said rail.

10. A casting machine comprising co-acting cope and drag members, one of which is provided in its casting surface with a longitudinally extending groove, a transversely extending longitudinally adjustable margin strip, and means carried by said margin strip for determining the length of the working portion of said groove.

11. A casting machine comprising co-acting cope and drag members, one of which has a longitudinally extending groove formed in its casting surface, and adjustable means for determining the length of the working portion of said groove.

12. A casting machine comprising co-acting cope and drag members hinged together at one end, the opposite end of one of said members being provided with a pouring gate, means for supporting said cope and drag members in a horizontal position, and other means extending from said cope and drag members in a direction away from said pouring gate for supporting said cope and drag members in a vertical position.

13. A casting machine comprising cope and drag members, one of said members being provided at one end with a pouring gate, means for supporting said members in a horizontal position, and means for supporting said members in a vertical position, comprising a leg secured to each of said members and extending in a direction away from said pouring gate.

In witness whereof, I hereunto subscribe my name this 13th day of December, 1921.

LOUIS E. LEYENS.
